DESIGN FOR A LIST FINDER

Albert Edward Pollock, New York, N. Y.

Application April 18, 1947, Serial No. 138,466

Term of patent 14 years

(Cl. D74—1)

To all whom it may concern:

Be it known that I, Albert Edward Pollock, a citizen of the United States and a resident of New York, county and State of New York, have invented a new, original, and ornamental Design for a List Finder, of which the following is a specification, reference being had to the accompanying drawings, forming part thereof.

In the drawings:

I claim:

The ornamental design for a list finder, substantially as shown.

ALBERT EDWARD POLLOCK.
